UNITED STATES PATENT OFFICE.

RICHARD HEINSOHN, OF MOUNT VERNON, NEW YORK.

WINDOW-SCREEN.

1,150,365.

Specification of Letters Patent.

Patented Aug. 17, 1915.

Application filed September 22, 1914. Serial No. 862,975.

To all whom it may concern:

Be it known that I, RICHARD HEINSOHN, citizen of the United States, residing at Mount Vernon, in the county of Westchester and State of New York, have invented certain new and useful Improvements in Window-Screens, of which the following is a specification.

This invention relates to improvements in window screens, and has for one of its objects to improve the construction and increase the efficiency and utility of devices of this character.

Another object of the invention is to provide a simply constructed device which is automatically adaptable to windows of varying widths between the side members and which may be readily inserted into and removed from a window frame without alteration or modification of the frame or the sashes.

With these and other objects in view the invention consists in certain novel features of construction as hereinafter shown and described and then specifically pointed out in the claims; and in the drawings illustrative of the preferred embodiment of the invention—

Figure 1 is a side elevation partly in section of one of the improved screens. Fig. 2 is an edge view of the same. Fig. 3 is a vertical section on the line 3—3 of Fig. 1. Fig. 4 is a section on the line 4—4 of Fig. 1. Fig. 5 represents portions of the frame members at one corner in perspective and separated.

Corresponding and like parts are referred to in the following description and indicated in all the views of the accompanying drawings by the same reference characters.

The improved device comprises in general a screen frame having side members and hollow end members and provided with the usual screen material bearing members spaced from the side members and extending in parallel relation thereto, springs within the hollow end members of the frame, and rods connected to the bearing members and extending into the hollow end members and coupled to the springs, the springs operating upon the rods to maintain the bearing members yieldably in their outer position. The bearing members are designed to engage the confronting faces of a window frame, and are preferably formed with a groove in their outer faces to engage guiding members attached to the window frame.

The side members of the frame to which the screen material is attached are represented as a whole at 10 and each provided with a longitudinally directed rabbet to receive the margins of the screen material, indicated conventionally at 11, the screen material being held in position in the rabbet by holding strips 12. The end members of the frame for the screen material each comprises a body portion 13 having a longitudinally directed cavity or pocket 14 closed at the ends as illustrated at 15 in Figs. 1 and 5. The body members 13 are united in any suitable manner at their ends to the side members 10, and one face of the end members is flush with one face of the side members, while the opposite sides of the end members are flush with the bottoms of the rabbets of the side members, so that the edge 75 of the screen material 11 will bear upon the inner portions of the hollow end members. A strip of sheet metal, indicated at 16, is disposed over the hollow end members and over the portion of the screen material bearing thereon and is turned outwardly at its outer edge as indicated at 17, the object to be hereinafter explained.

Bearing upon the outer face of the sheet metal member 16 is a filling strip 18 preferably of wood, the two portions 16—18 forming the closures to the hollows of the end members, the terminals of the members 16—18 engaging in the terminals of the rabbet portion of the side members 10. By this arrangement the outer faces of the members 18 and 12 and the body portion of the side members 10 are flush throughout, while the outturned edges 17 of the sheet metal strips extend slightly beyond the outer faces of the filler members 18, as illustrated in Fig. 3, to bear against the window sill, and likewise to bear against the adjacent face of the sash to exclude insects, as hereinafter explained.

The bearing members are disposed adjacent to the side members 10 of the frame and are represented as a whole at 19 and each formed with a longitudinal channel or groove 20 in the outer face adapted to engage guide strips of the usual form attached to the adjacent face of the window frame, the guide strips not being shown as their construction is so well known. Attached to each of the members 19 is a pull member 105 preferably U-shaped, as indicated at 22, and extending through suitable apertures or re-

cesses in the members 10 and projecting beyond the latter in convenient position for the operator to enable the members 19 to be drawn inwardly or toward the members 10.

- 5 Connected to each of the members 19 near their ends is a rod 23, each rod extending into the hollow portion 14 of the end members and lapping past each other at their inner ends as shown in Fig. 1 at the bottom.
- 10 Each rod is provided with a lateral offset or shoulder 24 which bears against the ends 15 of the cavities 14 to limit the outward movement of the rods. Each rod extends through a recess in the end of the member 13 and is held in position by a staple or other suitable holding means, illustrated at 25. By this means the rods are movable endwise, but cannot be displaced laterally. At their inner ends the rods are provided with hooks 15 opening away from each other, and connected at its terminals to each coacting pair of the hooks is a spring 27, the springs thus exerting their force to maintain the rods 23 in engagement with the terminals 15 of the pocket 14. By this means the members 19 are maintained yieldably in their outer position, or spaced away from the members 10, and movable inwardly toward the members 10 by a pulling force applied to the members 22. By this simple means the members 19 are readily adjustable to windows of varying widths, and will be retained in engagement with the guide strips by the action of the springs, as will be obvious. It will also be obvious that either or both of the members 19 may be drawn inwardly, as they operate entirely independent of each other.

The bearing members 19 are provided with covering members 28 which are connected to the members 19 and extend over the outer faces of the members 10, to guard and protect the latter and likewise to close the opening which would otherwise appear between the members 19 and 10. At their terminals the covering members 28 are provided with sheet metal tips 29 to strengthen the covering members and to prevent them from splitting. By this simple arrangement when the improved device is to be inserted in a window, the grooved side members 19 are fitted over the guide strips with the outwardly turned edge 17 of the lower hollow end member in engagement with the window sill and the outwardly turned edge 17 of the upper end member in engagement with the adjacent portion of the sash. By this means insects are effectually excluded, while at the same time the circulation of air is not shut off.

60 The improved device can be easily manu-

factured and applied without structural change in the frame or sash.

Having thus described the invention, what is claimed as new is:

1. A device of the class described comprising bearing members, a screen frame including side members and hollow end members, rods connected to said bearing members and extending into the hollows of said end members and lapping past each other therein, and a spring connected at its ends to the inner terminals of said rods. 65

2. A device of the class described comprising a screen frame including side members and hollow end members, bearing members 75 extending in parallel relation to the screen side members, rods connected to said bearing members and extending into said hollow end members and lapping past each other therein, and springs connected to the inner 80 terminals of said rods.

3. A device of the class described comprising a screen frame including side members and hollow end members, bearing members extending in parallel relation to the screen 85 side members, cover members connected to the bearing members and engaging over the screen side members, rods connected to said bearing members and extending into said hollow end members and lapping past each 90 other therein, and springs connected to the inner terminals of said rods. 95

4. A device of the class described, comprising a screen frame including side members and hollow end members, bearing members 100 extending in parallel relation to the screen side members, cover members connected to the bearing members and engaging over the screen side members, reinforcing tips at the ends of the cover members, rods connected to said bearing members and extending into said hollow end members and lapping past each other therein, and springs connected to the inner terminals of said rods. 105

5. A device of the class described comprising a screen frame including side members and hollow end members, bearing members extending in parallel relation to said side members, springs within the hollow end members, rods connected to said bearing 110 members and to said springs, and sheet metal closures to the hollows of the end members and outturned at one edge to form insect excluders. 115

In testimony whereof I affix my signature in presence of two witnesses.

RICHARD HEINSOHN. [L. S.]
